UNITED STATES PATENT OFFICE.

JAMES J. LAWLER, OF PELHAM, NEW YORK.

ILLUMINATED TILES FOR VAULTS, &c.

1,097,650.

Specification of Letters Patent. Patented May 26, 1914.

Application filed June 1, 1912. Serial No. 701,029.

To all whom it may concern:

Be it known that I, JAMES J. LAWLER, a citizen of the United States, and resident of Pelham, in the county of Westchester and State of New York, have invented certain new and useful Improvements in Illuminated Tiles for Vaults, &c., of which the following is a specification.

My invention relates to improvement in illuminated tiles for vault, area, dome and other places as used in reinforced concrete construction, the objects being to build up a complete light with a unit of a uniform size and construction, each unit consisting of a metallic receptacle and a glass placed therein.

Another object is to mount each glass separately in a metallic seating for quickly replacing glass in case of fracture, without disturbing the surrounding concrete.

A further object is to erect the complete light without the use of the conventional permanent iron frame in which illuminated tiles are usually placed.

My improvement is shown in the accompanying drawings in which—

Figure 1 is a central sectional view of a complete unit, the glass being either square or round. Fig. 2 is a plan view of Fig. 1 before the concrete is filled in. Fig. 3 is a sectional view on line X—X of Fig. 4. Fig. 4 is a plan view of a series of units mounted on a temporary wooden frame.

Similar characters of reference denote like parts in the several views.

The holder 1, is square at the base in plan view, and consists of the pocket, 1^a having a shoulder, 1^b, upon which the glass, 2, rests; below this shoulder the holder flares out at the base bell shaped, as shown at 1^c. The holder may be of cast or stamped metal, all its part being integral. The glass may be round, square or of any shape and may have depending prisms 8, as shown in Fig. 1, the shape and outline however, not being an essential feature of this invention. The glass is inserted in the holder and surrounded by a prepared putty, 5, which makes a water-tight joint between the glass and the metal holder.

In Figs. 3 and 4 there is shown a temporary wooden frame work or support. It consists of cross strips, 6, laid out in uniform spacings, upon which the metal holder rests; the supporting strips, 7, may be supported or held up in any preferred manner.

The wire rods, 4, may be anchored in any preferred manner.

Such being the construction the operation is as follows: When the wooden frame work has been erected in the opening to be covered, the metal units are placed in position, edge to edge. The reinforcing rods are placed in position, after which the cement or concrete is filled in on a line with the face of the holder and glass. When the concrete is set or hardened, the frame work is removed and the metal may be enameled or painted to suit, or this operation may be done before the glass is inserted and before the units are placed in position: in fact a vitreous enamel may be baked on after the metal units are formed and before inserting any glass. The glass may be inserted into the holder before or after the seating of the units.

Should a glass become broken, it is only necessary to apply pressure to the under side thereof, that is, through the lower bell-shaped side of the holder, to remove the same to permit a new glass to be inserted without disturbing the edge of the concrete adjacent to the holder. The glass being surrounded by the body of putty, it is less liable to fracture than when placed directly in the concrete and subjected to the pressure caused by expansion and contraction due to climatic or other conditions.

The shape of the metallic holder assures its positive retention in place in the concrete, which material is built up around and above the bell-shaped base, engaging the exterior of the shoulder and pocket, as shown in Figs. 1 and 2. Viewed from below, the tiling presents a metallic surface throughout, except the glasses,—and if white enameled, the transmitted light is reflected, owing to the shape of the holders at base.

What I claim is—

1. An illuminated concrete tiling composed of a series of uniformly shaped units, a glass for each of said units, each unit consisting of a metal holder shouldered both interiorly and exteriorly, the bottom edges of the adjacent units lying contiguous the glass adapted to be supported by the interior shoulder, a filling of concrete to surround said glass holders and retained in position by the exterior shoulders, and a plurality of reinforcing rods embedded in the concrete.

2. In a vault light a series of units of uniform shape and construction, each unit con-

sisting of a metal holder provided with interior and exterior shoulders, a bell-shaped base, the lower edge of each unit being rectangularly-shaped for engagement with each adjacent unit, a glass resting on said interior shoulder, a concrete filling between the units and flush with the surface of the glass and a series of reinforcing rods embedded in said concrete, and means for making a water-tight joint between said glass and said holder.

3. An illuminated vault light structure composed of a series of units, each unit consisting of a metal holder provided with an interior and an exterior shoulder, a glass carried by each unit and supported by the interior shoulder, each unit having the base portion thereof bell-shaped, the edges of which engage each adjacent unit and a filling of concrete between the several units.

4. An illuminated vault light structure composed of a series of units, each unit provided with interior and exterior shoulders, a glass supported by the interior shoulders,

said units having their lower edges rectangularly-shaped for engaging each adjacent unit, and a filling of concrete between the respective units and retained therein by the exterior shoulders.

5. An illuminated vault light structure composed of a series of units, each unit being formed of sheet metal and having a bend in its side wall at substantial right angles to provide an interior and exterior shoulder at the same point on the wall, each unit having its lower end flaring outwardly and being rectangularly-shaped, the bottom edge thereof engaging each adjacent unit, a lens mounted upon the internal shoulders, and a filling of concrete between the adjacent units to lie beneath the external shoulders.

Signed at New York city in the county and State of New York this 29th day of May A. D. 1912.

JAMES J. LAWLER.
